[57] ABSTRACT

A clock hand setting mechanism mounted upon the crystal of a clock and having a manually manipulatable setting stem whose axis is substantially coincident with the axes of the hour, minute, and second hand shafts which extend from the clock movement, the setting stem being adapted for longitudinal movement toward and away from the clock dial, with the extremity of the stem closest to the dial carrying at least one finger displaced from and running generally parallel to the axis of the stem for selectively engaging and rotationally adjusting the second and minute hands of the clock, the second hand being driven by the second hand shaft through a frictional clutch device to prevent damage to the escapement mechanism of the clock movement while the position of the clock hands are being adjusted.

CENTER SET FOR CLOCKS

BACKGROUND OF THE INVENTION

In the prior art, clocks having manually manipulated hand setting mechanisms mounted at a central location upon the clock crystal are well known. Generally a setting stem is journaled within an aperture in the clock crystal such that the axis of the stem is substantially coincident with the axes of the hour and minute hand shafts extending from the clock movement. The minute hand shaft is generally a solid rod journaled within a tubular hour hand shaft. A knurled knob is affixed to the extremity of the setting stem which is external to the clock crystal while the internal extremity of the stem is shaped to engage a splined receptacle or the like in the end of the solid minute hand shaft of the clock movement. The setting stem is further adapted for longitudinal movement along its axis and is spring biased to a normal rest position at which the internal extremity of the stem is out of engagement with the minute hand shaft.

To adjust the setting of the hands of such prior art clocks, one need only grasp the knurled knob on the setting stem, push the stem inwardly until it engages the minute hand shaft and then rotate the knob until desired setting of the clock hands is achieved.

While such a prior art "center set" arrangement is useful with clocks utilizing only hour and minute hands, it has inherent limitations in respect of clocks provided with second hands. In most instances the second hand is driven from a shaft which is coaxial with the tubular minute and hour hand shafts of the clock movement. Since the second hand is coupled to the second hand shaft by a hub which extends into the tubular minute hand shaft and grasps the second hand shaft, direct access to the minute hand shaft is not available. Moreover in clocks having such "top mounted" second hands, it is not practical to attempt setting the clock hands by directly engaging the second hand itself or the second hand shaft since the direct gearing of the second hand shaft to the internal clock movement shaft on which the escapement wheel is mounted would cause bending of the escapement pins if substantial manual rotational force were to be applied to the second hand shaft.

Clock mechanisms with top mounted second hands have considerable appeal to the public and those with remote setting mechanisms have been sold extensively. Therefore, the development of a mechanism adjustable from a center set mounted on the clock crystal is desirable for use with clocks having a top mounted second hand.

SUMMARY OF THE INVENTION

This invention is directed to a clock having a manually manipulatable clock hand setting mechanism mounted on the clock crystal and wherein the clock is provided with a top mounted second hand. The hand setting mechanism includes means for controlling the position of the second hand relative to the axis of the second hand shaft. More particularly, the invention is directed to a clock wherein the manually manipulatable clock hand setting mechanism is positioned on a crystal in front of the second hand. The invention is also directed to this type of clock in which a frictional coupling is interposed between the second hand and

the escapement means to avoid damage to the escapement means when the second hand is manually positioned.

More specifically the invention is directed to a clock 5 with hour, minute and second hands wherein the manually manipulatable clock hand setting mechanism is rotatable from a position external to the crystal and is connected to an engagement means for selective engagement and rotational adjustment of the second and minute hands of the clock. The features of the clock are particularly advantageous in respect to top mounted second hand arrangements requiring selective adjustment of the second and minute hands without damage to the escapement means. In addition, connection means are associated with the engagement means to permit transverse movement of the engagement means with respect to the axis of the second hand shaft. This feature enables the engagement means to move to the side of the second hand when initial contact is made on the front surface of the hand. Otherwise, continued force applied to the engagement means would result in bending of the second hand, the second hand shaft, associated linkages and possibly the minute hand.

25 In accordance with the present invention a clock is provided which has a manually manipulatable clock hand setting mechanism and includes in combination a clock movement with at least a second hand shaft extending therefrom for driving a time indicating hand affixed to the shaft. The shaft is mechanically coupled to an escapement means integral with the clock movement. A manually manipulatable means is provided for selectively engaging the second hand for controlling its 30 position about the axis of the second hand shaft. A torque limiting clutch means is interposed between the second hand and the escapement means to prevent damage to the escapement means during adjustment of the second hand. Preferably the clock is constructed with a center set mechanism having built-in rotational 35 lost motion or mechanical "play," in respect of the second hand shaft axis to permit the engagement means to move off to the side of the second hand or minute hand in the event that the engagement means is forced against the front surface of either hand. Also, the front surface of the second hand is shaped to encourage 40 movement of the engagement means to the side of the hand in the event that contact is made. Still further in accordance with the present invention the second hand 45 is resiliently coupled to its shaft to permit some movement of the second hand towards the dial in the event that the engagement means fails to move to the side of the hand.

50

DESCRIPTION OF THE DRAWINGS

55 In the drawings:

FIG. 1 is a front view (without crystal) of an automobile clock illustrating the dial and hands.

60 FIG. 2 is an expanded view of the coaxially mounted shafts of the movement and the second, minute, and hour hands.

FIG. 3 is a section taken along the line 3-3 of FIG. 2 showing by cross-section the shape of the second hand designed to force the finger to the side.

65 FIG. 4 is a section view along the axis of the center set and the coaxially mounted shafts showing a finger arrangement wherein two fingers are peripherally

mounted on a plate and includes a block diagram representing conventional escapement means of the movement connected to the second hand shaft.

FIG. 5 is a similar view of the center set mechanism and illustrates a plate which utilizes one finger.

FIG. 6 is a side view of a plate showing the shape of the finger shown in FIG. 5.

GENERAL DESCRIPTION

The invention is directed to a clock having a manually manipulatable clock hand setting mechanism and including in combination a clock movement having at least a second hand shaft extending from the movement for driving a time indicating hand affixed to the shaft. The shaft is mechanically coupled to an escapement means within the clock movement. The manually manipulatable means serves to control the position of the hand relative to the axis of the second hand shaft. A torque limiting clutch means is interposed between the second hand and the escapement means to prevent damage to the escapement means during positioning of the second hand. The clock has a crystal positioned in front of the second hand and the manually manipulatable means comprises a rotatable means which extends through an opening in the crystal and is connected to an engagement means positioned beyond the periphery of the second hand shaft and directed towards the second hand of the clock. Usually, hour and minute hands are present and the rotatable means and engagement means are movable towards the hands to selectively engage and rotationally adjust the second and minute hands of the clock.

In more detail, the clock has a movement and a casing for the movement including a dial and crystal. The dial has a centrally located opening in which hour, minute and second hand shafts of the movement are coaxially mounted with respect to one another. Hour, minute and second hands each are mounted on one of the shafts with the hour hand being positioned closest to the dial. The movement includes escapement means which is connected to the second hand shaft and frictional torque limiting means are interposed between the second hand and the escapement means.

The crystal is positioned in front of the dial and has an opening located directly in front of the shafts. Engagement means are located in a normal rest position immediately adjacent the inner surface of the crystal, with one or more fingers extending beyond the periphery of the shafts and extending toward the hands of the clock. Rotatable means extending through the crystal opening are connected to the engagement means and are movable towards the hands to selectively engage and rotationally adjust the second and minute hands of the clock. Means are also provided for biasing the rotatable means and engagement means to their normal rest position. In the combination of engagement means and rotatable means, connection means are provided to permit transverse movement of the engagement means with respect to the axis of the second hand shaft. This movement can be in the form of lost-motion or mechanical "play" to permit the finger or fingers of the engagement means to move to the side of the second or minute hand in the event that contact is made with the front surface of either hand. In addition the finger or fingers are advantageously constructed of

flexible material and the resultant resilience of the finger prevents damage to the second hand and second hand shaft. Similar benefits in respect of the minute hand are also obtained. In addition each finger when positioned over a hand is transverse to the axis of the hand and lays generally in a plane which is skewed relative to this axis. Also, the two opposing side walls of the finger generally along the periphery of the plate are tapered towards the clock hand and the tip of the finger is rounded. These features enable the resilient finger to move to the side of the hand when contact is made with the front surface of the hand and particularly when such surface is in the form of an inverted "V" or other form with an apex which aids in the lateral movement of the finger.

In more particularity attention is now directed to FIG. 1, in which a clock 10, is shown including a casing 12 for housing the clock movement and a dial 14 with time indicia delineated thereon. Centrally located hub 16 is mounted on the shaft for the second hand 18 (as more completely illustrated in FIG. 4). Second hand 18, minute hand 20, and hour hand 22 are also illustrated.

FIG. 2 is an enlarged view of the hub and underlying coaxially mounted shafts. As illustrated, front hub 16 is mounted on inner shaft 24 and top mounted second hand 18 is frictionally and resiliently mounted to this arrangement. Minute hand 20 is rigidly attached to shaft 26 in a customary manner. As with conventional clocks, shaft 26 of the movement is interconnected with associated linkages to hour hand 22 so that motion of the minute hand 20 provides controlled movement of the hour hand 22. Hour hand 22 as illustrated in FIG. 2 is connected to outer shaft 28.

FIG. 3 illustrates a sectional view of the second hand 18 showing the outer surface 30 shaped to force the finger to the side of the hand in the event that the finger is forced against the outer surface of the hand. As illustrated, the shape is in the form of an inverted "V" although other forms such as an inverted "U" and the like may be utilized. Minute hand 20 also is advantageously designed with a similar cross section although considerably thicker.

Turning now to FIG. 4, there are illustrated three coaxially mounted shafts 24, 26 and 28, corresponding to the second-hand shaft, the minute-hand shaft and the hour-hand shaft of the clock movement. Second-hand 18, minute-hand 20 and hour hand 22 are respectively mounted to these shafts. The second-hand shaft 24 is generally directly geared to the clock movement escapement means as indicated by the dotted line 67 extending therefrom to the block 29.

With further reference to FIG. 4, and more particularly the lefthand portion thereof, the manually manipulatable clock hand setting mechanism of the present invention is illustrated. A setting stem 32 shown in its normal rest position extends through an opening 34 of the clock crystal 36. The axis of the setting stem 32 is substantially coincident with the axes of the shafts 24, 26 and 28. At the righthand or internal extremity of the stem 32 a plate 38 is loosely coupled to a turned down reduced diameter portion of the stem 32. The plate 38 carries fingers 40 and 42 which are spaced apart so as to engage the second-hand 18 and the minute-hand 20 when the stem 32 is urged toward

the clock hands. The plate 38 is captured on the turned down portion of the stem 32 by suitable means such as the enlarged portion 44 which can be formed by peening the material comprising the shaft 32 after the plate 38 has been mounted thereon. The mechanical coupling between the plate 38 and the stem 32 is made purposely loose so that if the fingers 40 and 42 directly engage the surface of either the second-hand or minute-hand, the fingers will tend to slide off to one side or the other of the hands as generally described in connection with FIG. 3. In this regard it is preferable to mount the plate 38 on the stem 32 such that some rotational lost motion is permitted between the plate 38 and the stem 32 when the latter is rotated. This may be accomplished by a variety of means such as for example indicated by the key 45 shown in dotted lines. The slot with which the key cooperates is made substantially larger than the width of the key. Additionally, the plate 38, although normally resting in a plane parallel to the inner surface of the clock crystal 38, may be easily skewed. This freedom of motion is ensured by making the diameter of the hole in the plate somewhat larger than the diameter of the turned down portion of the stem 32. This ensures that in the event both fingers 40 and 42 fall upon the same side of both arms of the second or minute-hand, the forcing of the stem 32 toward the hands will not tend to bend the hands.

With further reference to FIG. 4 it can be seen that the set stem 32 is biased by spring 50 acting upon the inner surface 48 of the set knob 46 to a normal rest position at which the fingers 40 and 42 are disengaged from the hands of the clock. One end of the spring 50 engages the surface 52 of the set knob 46, while the other end of the spring 50 rides against the surface of a boss 54 on the crystal 36. The length of the stem 32 is so established as to permit longitudinal movement of the fingers 40 and 42 to a position adjacent either the second-hand 18 or the minute-hand 20 without reaching the hour-hand 22. Movement of the minute-hand, of course, will cause the desired movement of the hour-hand 22 when setting the hands of the clock.

In further accordance with the present invention and as illustrated in FIG. 4, the second-hand 18 is frictionally and resiliently coupled to the second-hand shaft 24. This obviates damaging the second-hand in the event that the fingers 40 and 42 engage the same on its upper surface without sliding off to either side thereof while the stem 32 is forced in a direction to engage the minute-hand 20, and at the same time obviates damage to the clock movement escapement means when the second-hand 18 is rotated by the fingers 40 and 42. To this end the spring 60 serves as a biasing means and forces the second-hand 18 at the surface 58 thereof to form a frictional torque restraining clutch mechanism with the surface 62 of hub 16. The end 63 of spring 60 in turn acts against the flange 64 which is affixed to the hub by a suitable means such as upsetting the periphery of the hub or the like. The spacing between the surface 62 of the hub 16 and the surface of flange 64 against which the spring 60 acts is such as to permit the second-hand to be tilted away from its normal rest position to an extent where the end of the second-hand comes into close juxtaposition to but does not touch the surface of the minute-hand. This degree of play is generally sufficient to prevent either the

bending of the second-hand itself or the second-hand shaft 24 when the fingers fail to slip off to the sides of the hand.

A still further embodiment of the present invention is shown in FIG. 5 which is in all respects substantially identical to the arrangement shown in FIG. 4 except that only one finger shown at 70 is attached or made integral with the plate 71. This obviates the possible bending of the hand as is inherent with the use of two fingers when falling on the same side of the hand. In this embodiment the plate 71 can be fitted to the stem 32 with closer tolerances so as to minimize the transverse looseness of the plate upon the stem 32 as by making the diameter of the hole in the plate 71 closer to the diameter of the reduced portion of the pin 32.

Still further in accordance with the present invention, and as illustrated in FIGS. 4 and 5, it can be seen that the plane in which each of the fingers 40, 42 and 70 generally lay is skewed relative to the axes of the stem 32. The fingers are accordingly made of a flexible material such as polypropylene, polyethylene, nylon or the like and sufficiently thin so that in the event the fingers directly engage the second-hand 18 or the minute-hand 20, they will tend to yield longitudinally along the axes of the hands and exert a force thereon less than that required to permanently bend the hands.

Turning now to FIG. 6 there is there illustrated a side view of fingers 70 showing the taper of the side 72 and the curved surface of the end 74. This configuration may, of course, be used in connection with the fingers 40 and 42 shown in FIG. 4. Finger 70 is positioned (as illustrated in FIG. 4) with the taper 72 and 75 and curved or rounded end 74 being in the direction of second hand 18. These features cause finger 70 to move to the side of second-hand 18 or to move hand 18 in a lateral direction with respect to finger 70. The taper 72 and 75 is controlled to avoid excessive taper and the development of a binding force against hand 18. Preferably there is less finger taper in the vicinity of the minute hand to ensure a more positive setting drive thereon as shown at 72a in FIG. 6.

The foregoing description of the present invention is only illustrative of an exemplary form which the invention may take. Still, other modifications and variations will suggest themselves to persons skilled in the art. It is intended, therefore, that the foregoing detailed description be considered as exemplary only and that the scope of the invention be ascertained from the following claims.

What is claimed is:

1. A clock having a movement, a casing for the movement including a dial and a crystal, the crystal having a centrally located opening, said movement including hour, minute and second hand shafts coaxially mounted with respect to one another and escapement means connected to the second hand shaft, said shafts extending to the front of the dial, an hour, a minute, and a second hand each respectively mounted on a corresponding one of said shafts, with the hour hand closest to the dial, frictional torque limiting means interposed between the second hand and said escapement means, said crystal being positioned in front of the dial with said opening located directly in front of said shafts, engagement means normally positioned adjacent the inner surface of said crystal beyond the

periphery of the shafts and extending toward the hands of the clock, rotatable means extending through said crystal opening, connected to said engagement means and movable toward the hands to selectively engage directly and rotationally adjust the second and minute hands of the clock.

2. A clock according to claim 1 wherein said second hand is top mounted in respect to said hour and minute hands.

3. A clock according to claim 1 which includes means for biasing the rotatable means and engagement means to their normal position away from said hands.

4. A clock according to claim 1 wherein the engagement means comprises at least one finger connected to the rotatable means.

5. A clock according to claim 4 wherein said finger is differentially tapered along its sides with less taper along those portions thereof which are adapted to engage the minute hand.

6. A clock according to claim 1 wherein the front surface of said second hand is shaped to produce movement of said engagement means when the engagement means contacts the front surface of the second hand, said second hand shaft having a longitudinal axis, and

said rotatable and engagement means including connection means to permit transverse movement of the engagement means in respect to the axis of the second hand shaft.

5 7. A clock according to claim 6 wherein the clock includes means for biasing the rotatable means and engagement means to their normal position away from said hands, said engagement means comprises at least one flexible finger connected to the rotatable means, 10 and said second hand is mounted on top of said hour and minute hands.

8. A clock according to claim 7 wherein the second and minute hands have outer surfaces shaped to force said finger in a transverse direction when the finger is 15 forced against the front surface of either hand, and said finger is constructed of a flexible material.

9. A clock according to claim 7 wherein said frictional torque limiting means is interposed between said second hand and said second hand shaft and said finger 20 is in a plane skewed in respect to said stem.

10. A clock according to claim 9 wherein said second hand is frictionally and resiliently coupled to said second hand shaft.
